SPHERICAL SEGMENT TANK AND METHOD
OF MAKING SAMEChristian Arne, Chicago, Ill., assignor to Chicago
Bridge & Iron Company, a corporation of Illinois

Application February 23, 1950, Serial No. 145,770

6 Claims. (Cl. 220—1)

1

This invention relates to improvements in pressure tanks and methods of making the same and more particularly segmental and multisphere tanks.

Large pressure tanks are made of a plurality of steel plates usually welded together to form the completed enclosure, such as multisphere tanks shown in Boardman Patent No. 2,457,118. When such a tank is built up from a fixed foundation or support many of the welds must be vertical and overhead welds which are much more difficult to make accurately and sound than down hand welds. The present invention provides a method of making a pressure tank which obviates the difficulties attendant with welds made in positions other than down hand.

An embodiment of this invention is illustrated in the accompanying drawings, in which:

Fig. 1 is a vertical cross section through a pair of ring members mounted on rollers and showing two plates of the center segmental shell in place thereon;

Fig. 2 is an end view of a ring member illustrated in Fig. 1 showing three plates of the center segmental shell in position thereon;

Fig. 3 is a vertical view of a tank of this invention showing the plates of the center segmental shell in position and a portion of one end semispherical shell;

Fig. 4 is a view of the completed segmental tank partly in section;

Fig. 5 is a vertical view taken substantially along line 5—5 in Fig. 4;

Fig. 6 is an enlarged sectional view of a section of the ring member and plates of the adjacent shells and the diaphragm; and

Fig. 7 is a view of the completed tank mounted on an earth foundation.

The first step in construction of a tank according to this invention is the forming of an angle iron into a ring 10 and welding the ends of the angle iron together so that the ring is continuous. One leg 11 of the ring should extend radially inward and the other leg 12 should extend at an angle thereto. The rings 10 may be formed on the ground and a diaphragm 13 welded to the inwardly extending leg 11 of the ring member so formed. Thus the weld 14 between the ring member 10 and the diaphragm 13 may be a down hand weld, that is a weld in which the weld metal is deposited directly below the welding rod.

While the ring member 10 is illustrated as formed from an angle iron, other structural shapes may be utilized. Tanks for different services have various sizes and shapes and in conformity with the individual tank design, the ring member may be made up of an angle, a T, an I-beam, a bar or other section.

The next step is to mount a pair of rings 10 on a set of rollers 15 and 16, so that the rings 10 extend in parallel vertical planes and may be rotated on the rollers 15, 16. While the ring members are held in position on the rollers individual plates 17, 17a, 17b etc. may be welded to the base of the ring members as more clearly illustrated in Fig. 6. Each center plate of the center spherical section is welded to the ring members while the rings are rotated to a position so that the weld between the plate and the ring member is a down hand weld. As illustrated in Fig. 6 a portion of the weld between the plates 17 and the ring 10 is on the outside of the tank and another portion of the weld is on the inside. Each of these portions of the weld are performed by down hand welding. Successive plates 17 are placed 25 between the upstanding ring assemblies and welded in place sequentially while sequentially rotating the ring members on the roller supports so that each weld is a down hand weld. While rotating the ring assemblies the ring members roll over the rollers much like a wheel.

A preferable method of welding each of the plates to the ring members is to mount a welding station above the apex or the lowest point of travel of the ring members. The welding station is shown diagrammatically in Fig. 1 as a platform 40 supported by a construction framework (not shown). The welder may weld the successive plates of the spherical segments to the ring members as they are rotated up to a position under the welding station. A welding machine may be mounted above the apex or the lowest point of travel of the ring to weld each successive plate to the ring member or the welding may be done by hand. In either instance each weld will be a down weld.

After all the plates of the center spherical section have been welded between the ring members, the individual plates 18, 18a, 18b, etc. of an end semispherical section are welded to the outstanding leg 12 of the ring member 10 while sequentially rotating the ring members on the rollers for

3

making each weld in a down hand position. After one end spherical section has been welded to a ring member, the other end spherical section may be welded to the other ring member while sequentially rotating the rings for down hand welding to complete the segmental tank having three sections as illustrated in Fig. 4. An example of a tank made by this method, is one of approximately 15,000 barrels capacity and designed for a working pressure of about 80# per square inch.

A spherical tank may be constructed by the methods herein disclosed. A center section of the spherical tank is constructed with suitable rims, spokes and stiffeners and mounted on rollers for rotation about a horizontal axis. Plates of end sections of the spherical tank are then welded to the center section while sequentially rotating the center section to provide for down hand welding on each plate.

A multisphere tank such as shown in Fig. 4 may be supported on cradles 20 at the center sections under each ring member or may be supported on a foundation 21 of sand, concrete or the like, in the manner illustrated in Fig. 7. The diaphragms 13 may have openings 13a therethrough if desired.

Each of the segments are spherical in their layout to withstand a greater pressure with a lesser thickness of metal. The method described above for constructing the tank has several advantages in that it permits down hand welding of all the plates and allows complete drainage both inside and outside the tank.

The end spherical sections join the center section at such an angle that liquid may drain by gravity from the end sections into the center section where the inlet and outlet pipe 22 is usually connected with the tank. The slope of the adjacent portions of the sections at the lowest point on the intersection is downwardly toward the center of the segmental shell having the greatest diameter. The diaphragm is so constructed to permit the drainage to the lowest point in the tank. In the same manner, gas may flow without obstruction from the top of the end sections to the highest point in the tank. Water will run off the outside of the tank since there are no pockets to retain it.

In liquid containing tanks, the plate thickness on the bottom of the tank must be greater than the plate thickness at the top of the tank because the pressure is greater at the lower level. Plates extending generally upwardly on the tank thus have excess thickness to a degree increasing with the height above the lower edge of the plate. As best seen in Fig. 3, the plates of the spherical sections are arranged with their sides extending along meridians of the spherical section as determined by the intersection of planes passing through the polar axis of the section, with the surface of the section. Each plate has its greatest length in a generally horizontal direction and allows successive plate thickness to be selected to effect economy of construction. Also, plates arranged as illustrated in Fig. 3, have their edges deviating the least from parallel lines, thus providing for the least amount of waste in fabricating the individual plates for a tank.

It will be noted from Fig. 6 that the ring member 10 provides a three-way connection between the plates 18 of the end semispherical section, the plates 17 of the center section and the diaphragm 13. However, all welds at the joint illustrated are two-way welds since the plates 18 are

5 10 15 20 25 30 35 40 45 50 55 60 65 70 75

welded to the leg 12 of the ring members and the diaphragm is welded to the other leg 11 and the plates 17 of the center section are welded to the base of the angle iron with which the ring member is formed.

In the completed structure as illustrated in Figs. 4 and 7 the three segments of the tank have a common horizontal axis with the center section having a greater radius than the end semispherical sections. The intersection between the spherical sections lies in a plane passing through the ring members 10.

The foregoing detailed description has been given for clearness of understanding only and no unnecessary limitations should be understood therefrom.

I claim:

1. A multisphere tank comprising a plurality of spherical segmental shells intersecting along 20 parallel vertical planes, a ring girder interposed between adjacent shells and welded to the shells, each of said shells being welded to a separate portion of said ring girder, and a diaphragm welded to each ring girder, said shells having a common horizontal axis and each of said shells being less than a hemisphere with one shell having a radius greater than the other shells.
2. A three-segment multisphere tank comprising a pair of spaced parallel vertically aligned 25 ring girders, a spherical segmental shell welded to the girders to enclose the space therebetween, a first semispherical shell welded to one girder and a second semispherical shell welded to the other girder, all of said shells having a common horizontal polar axis and said segmental shell having a greater radius than the semispherical shells.
3. A tank as claimed in claim 2 in which the 30 shells are made up of a plurality of plates welded together and in which all of said welds are down welds.
4. A tank as claimed in claim 2 in which said 35 shells comprise a plurality of plates each having its longitudinal edges spaced along a meridian of the shell determined by a plane passing through the poles of the shell.
5. A tank as claimed in claim 2 in which the 40 portion of the spherical segmental shell and semispherical shell adjacent the ring girder slope downwardly toward the center of the spherical segmental shell at the lowest point on the shells.
6. The method for constructing a three-segment tank having spherical segments which comprises forming an angle iron into a ring with 45 one leg of the angle projecting radially inwardly from the angle, mounting a pair of rings so formed in spaced relationship for rotation in parallel vertical planes, positioning a welding device above a portion of the path of said rings, positioning an individual plate to extend between the spaced 50 rings to be aligned thereby and welding the ends of the plate to the rings, successively positioning additional plates between the rings in similar manner and welding the ends of said plates to the rings and to the previously welded plates 55 at the longitudinal edges after rotation of the rings to position the plates under the welding device to complete the inner spherical segment, aligning individual plates of the end segments with the rings, and then sequentially welding the individual plates forming the end spherical segments to another portion of the rings while sequentially rotating the rings.

CHRISTIAN ARNE.
